JOHN F. O'CONNOR, OF CHICAGO, ILLINOIS, ASSIGNOR TO WILLIAM H. MINER, OF CHAZY, NEW YORK.

BUFFER MECHANISM FOR PASSENGER-CARS.

1,251,685.

Specification of Letters Patent.

Patented Jan. 1, 1918.

Application filed March 30, 1917. Serial No. 158,495.

To all whom it may concern:

Be it known that I, JOHN F. O'CONNOR, a citizen of the United States, residing at Chicago, in the county of Cook and State 5 of Illinois, have invented a certain new and useful Improvement in Buffer Mechanism for Passenger-Cars, of which the following is a full, clear, concise, and exact description, reference being had to the accompanying drawings, forming a part of this specification.

This invention relates to improvements for buffer mechanism for passenger cars.

Heretofore considerable difficulty has been experienced in arrangements of buffer mechanisms for passenger cars in obtaining and maintaining the proper spring pressure on the buffer plates when two cars are coupled together. As is well known, it is desirable 20 that the buffer plates of two adjacent cars be maintained in constant contact during operation of the cars and at the same time the outward yielding pressure against the buffer plates must not be so great as to prevent proper and easy coupling of the cars when the same are brought together. Furthermore, due to the wide range of movement necessary for the buffer plates, it has heretofore been necessary to so design the 25 buffer mechanism that considerable compression thereof was necessary when two cars were brought together which resulted in forming too stiff a resistance to the buffer plate during the coupling action.

The object of the present invention is to provide a buffer arrangement wherein the buffer plate is forced inwardly a relatively short distance during the coupling together 30 of two cars and furthermore, to so arrange the yielding resistance for the buffer plate that it will not exceed a predetermined amount during the coupling of the cars.

Another and more specific object of the invention is to provide a buffer arrangement so designed that the buffer plate, during the coupling of the cars, is resisted in its inward movement by a spring which is independent of the main shock absorbing device of the buffer and furthermore, the 45 yielding resistance is so mounted that it will remain substantially uniform against the buffer plate so long as the latter and the coupler are maintained in alinement.

In the drawing forming a part of this 50 specification, Figure 1 is a vertical longitu-

dinal section of the end portion of a passenger car showing my improvements in connection therewith, and Fig. 2 is an enlarged vertical transverse section of the structure illustrated in Fig. 1 and taken on the line 2—2 thereof.

In said drawing, 10 denotes the end platform casting of a passenger car in which is mounted a relatively high capacity main friction buffer mechanism 11, the latter 55 having a rear stop 12 provided therefor and a front follower 13. The end of the casting 10 is recessed, as indicated at 14, in the usual manner to accommodate the center or main buffer stem 15, which engages the inner face 70 of the buffer plate 16. The details of the diaphragm and diaphragm face plate which are usually supported by the buffer plate are omitted inasmuch as the same do not form any part of this invention. Secured to the 75 underframe of the car are stop castings 17 with which is associated the draft gear 18 of the car, said gear 18 being connected with the coupler shank 19 by means of a yoke 20 in any desired or well known 80 manner. Secured to the coupler shank 19 is an upstanding relatively heavy bracket 21 which is perforated, as indicated at 22, to accommodate a forwardly extending post 23 formed on the follower 13 of the buffer 85 mechanism. The buffer stem 15 is provided with a flange 24 and a post or thrust member 25 at the rear thereof and in alinement with the rear post or thrust member 23. Said posts or thrust members 90 23 are maintained in alinement by means of a bushing or sleeve 26 slidably mounted thereon between the upstanding bracket 21 and the flange 24. Mounted on the bushing 26 and also interposed between the 95 bracket 21 and flange 24 is a spring 27 so designed that the opposed ends of the posts 23 and 25 are slightly separated, as indicated in Fig. 1, when the cars are coupled. In this connection, it may be stated that the 100 dotted lines in Fig. 1, indicate the release position of the buffer plate when the car is not coupled with an adjacent car and the full lines indicating the buffer plate in Fig. 1 show the position assumed when the cars 105 are coupled which will place the spring 27 under compression as will be understood.

With the arrangement above described, it is apparent that upon inward movement of the buffer plate during the operation of the 110

train, the buffer stem 15 will be forced rearwardly until the post 25 engages the post 23 whereupon the main buffer mechanism 11 will be brought into action. During this inward movement of the buffer plate 16, it is apparent that it will be maintained in alignment with the coupler and the bracket 21 carried by the shank of the coupler will move in unison with the coupler. Upon outward movement of the buffer plate and consequent outward movement of the coupler or draft on the draft gear 18, the buffer plate and coupler will still be maintained in alignment and at the same time the buffer plate 16 will be maintained in constant contact with the opposed buffer plate of the next car with a uniform pressure from the spring 27, since the latter moves forward bodily due to the forward or outward movement of the bracket 21 with the coupler.

With the foregoing described construction, it is apparent that the buffer plates of two cars coupled together will be maintained in firm contact and without the necessity of employing the main shock absorbing element of the buffer, under normal conditions, and upon inward movement of the buffer plate under a buffering action, the main shock absorbing element of the buffer will be brought into play and without the employment of the draft gear in any way to resist said inward movement of the buffer plate whereby the draft gear is utilized entirely for absorbing the shocks imposed thereon through the coupler and its shank.

I claim:

1. In car construction, the combination with a buffer plate and a shock absorbing buffer, of a draw bar, shock absorbing means coöperable with the draw bar, and means, governed by the position of the draw bar, interposed between the buffer plate and the shock absorbing buffer, for yieldingly controlling the position of the buffer plate.
- 45 2. In car construction, the combination with a buffer plate and shock absorbing buffering mechanism, of an extensible buffer stem interposed between said plate and mechanism, a draw bar, and yieldable means interposed between one element of said stem and the draw bar.
- 55 3. In car construction, the combination with a buffer plate having a plunger extending inwardly therefrom, of a draw bar, cushioning means interposed between said plunger and draw bar, a shock absorbing

buffering mechanism, and a thrust member interposed between said plunger and mechanism and adapted to actuate the buffer mechanism after a predetermined movement of the buffer plate.

4. In car construction, the combination with a buffer plate, a shock absorbing buffering mechanism, and a multiple piece buffer stem interposed between said plate and mechanism and having a predetermined amount of lost motion therebetween, of a draw bar and extension from the draw bar, and spring means between said extension and the part of said stem co-acting directly with the buffer plate whereby to maintain the buffer plate and coupler of the draw bar in relatively fixed positions during their movements when the car is coupled to an adjacent car.

5. In car construction, the combination with a buffer plate, a shock absorbing buffering mechanism, a two-part stem extending between the plate and the buffer mechanism, said parts being capable of relative approach and separation, of a draw bar, a draft gear to which the draw bar is operatively connected, a bracket movable in unison with the draw bar, and spring means interposed between said bracket and that part of the stem directly operated by the buffer plate.

6. In car construction, the combination with a draw bar and draft gear to which it is operatively connected, of a buffer plate, shock absorbing buffering mechanism, yielding means interposed between the draw bar and said buffer plate, and means interposed between the buffer plate and said mechanism arranged to actuate the latter after said yielding means have been compressed a predetermined amount.

7. In car construction, the combination with a buffer plate, a shock absorbing buffering mechanism, a two-part buffer stem interposed between the plate and the buffer mechanism and having the parts normally separated, a flange on that part of the buffer stem directly actuated by the buffer plate, of a draw bar, a bracket secured to and movable in unison with the draw bar and extended upwardly, said bracket being perforated to accommodate that part of the stem adjacent said mechanism, and a spring interposed between said bracket and said flange.

In witness that I claim the foregoing I have hereunto subscribed my name this 27th day of March, 1917.

JOHN F. O'CONNOR.
